US0D1106885S

(12) **United States Design Patent** (10) **Patent No.:** **US D1,106,885 S**
(45) **Date of Patent:** **** Dec. 23, 2025**

(54) **VEHICLE AND/OR REPLICA**

(71) Applicant: **Daimler Truck North America, LLC**,
Portland, OR (US)

(72) Inventors: **Malcolm Young**, Tigard, OR (US);
Jeffrey Cotner, Portland, OR (US);
Austin Wipf, Milwaukie, OR (US);
Jason McGinnity, Portland, OR (US);
Austin Cox, Portland, OR (US)

(73) Assignee: **Daimler Truck North America, LLC**,
Portland, OR (US)

(**) Term: **15 Years**

(21) Appl. No.: **29/996,920**

(22) Filed: **Apr. 3, 2025**

(57) **CLAIM**

The ornamental design for a vehicle and/or replica as shown and described.

DESCRIPTION

FIG. 1 depicts a front, top, left perspective view of a vehicle and/or replica showing our new design.

FIG. 2 depicts a front, right, lower perspective view thereof; FIG. 3 depicts a rear, right, upper perspective view thereof; FIG. 4 depicts a front view thereof; FIG. 5 depicts a back view thereof; FIG. 6 depicts a left side view thereof; FIG. 7 depicts a right side view thereof; FIG. 8 depicts a top view thereof; and, FIG. 9 depicts a top view thereof.

The ghosted or low contrasted showing of the vehicle and/or replica is provided for the purposes of illustrating portions that form no part of the claimed design. The dashed lines depict the boundary between the claimed design and portions that are not part of the claim.

1 Claim, 8 Drawing Sheets
